UNITED STATES PATENT OFFICE.

MARTIN LAERNOES AND JOHN DUNN, OF STREATOR, ILLINOIS, ASSIGNORS TO THE VULCAN DETINNING COMPANY, OF NEW YORK, N. Y., A CORPORATION OF NEW JERSEY.

MACHINE FOR COMPRESSING DETINNED OR OTHER SCRAPS.

SPECIFICATION forming part of Letters Patent No. 737,425, dated August 25, 1903.

Application filed March 26, 1903. Serial No. 149,682. (No model.)

To all whom it may concern:

Be it known that we, MARTIN LAERNOES, a citizen of the Kingdom of the Netherlands, and JOHN DUNN, a citizen of the United States, both residing in Streator, in the county of LaSalle and State of Illinois, have invented certain new and useful Improvements in Machines for Compressing Detinnd or other Scraps, of which the following is a specification.

This invention relates to certain improvements in machines for compressing detinnd and other scraps, for which we filed an application for Letters Patent on January 10, 1903, Serial No. 138,511, whereby the construction of the same is considerably simplified and the scraps instead of being compressed in the receiving-boxes into blocks on a special anvil below the box and delivered from the machine by withdrawing the anvil-block by means of a special cylinder and piston, are compressed on a stationary anvil-block in the foundation-plate and then moved with the box over to an opening in the foundation-plate and delivered, in connection with a reciprocating plunger, through said opening to a delivery-chute below the foundation-plate simultaneously with the compression action, which takes place in the next following box by the action of the reciprocating compressing-plunger. By this arrangement the time taken up for withdrawing the anvil and delivering the compressed package of scraps from the same is saved, for the reason that the delivering of the package of scraps now takes place at the same time as the compressing action in the next receiving-box takes place; and for this purpose the invention consists of a machine for compressing detinnd and other scraps which comprises a plurality of receiving-boxes, a foundation-plate below the same having an opening, a stationary anvil in said opening, a vertically-reciprocating plunger located vertically above one of said receiving-boxes and the anvil, means for imparting a step-by-step motion to said receiving-boxes, a second opening in said foundation-plate at some distance from the anvil and reciprocating plunger and corresponding in size to the in-

ner opening of the receiving-boxes, a second reciprocating plunger acting vertically above said second opening, and means for delivering the blocks of compressed scraps below the second opening in the foundation-plate. 55

The invention consists, further, of certain additional details of construction, which will be fully described hereinafter and finally pointed out in the claims.

In the accompanying drawings, Figure 1 is 60 a side elevation of our improved machine for compressing detinnd and other scraps. Fig. 2 is an end elevation of the same. Fig. 3 is a plan view of the receiving-boxes, partly in horizontal section on line 3 3, Fig. 2; and Fig. 65 4 is a top view of the receiving-boxes, showing the plunger operating the same.

Similar letters of reference indicate corresponding parts.

Referring to the drawings, A represents the 70 foundation-plate of our improved machine for compressing detinnd and other scraps. The foundation-plate is preferably made in the shape of a disk and of sufficient strength to support a number of receiving-boxes B, 75 which are made of rectangular, round, or other cross-section and reinforced at their upper ends by retaining-frames b and at their lower ends by exterior strengthening-straps b' of corresponding shape. Each receiving- 80 box is composed of two parts, provided with perforated ears n, that are connected by means of fastening-bolts n'. The receiving-boxes B may also be made of one integral piece, so as to do away with the fastening- 85 bolts. They are made thicker at their lower ends, so as to resist the strain to which they are subjected when compressing the scraps. The inner ends of the upper parts of the receiving-boxes are slightly rounded off or tapered, so as to facilitate the feeding of the scraps from a platform K, which surrounds the upper ends of the receiving-boxes. A plurality of receiving-boxes are arranged on the foundation-plate, six being shown in the 90 drawings. The receiving-boxes are arranged in a circle equidistantly from each other and connected at their lower ends by a ring-shaped frame B', provided with openings 95 corresponding in shape and size to the re- 100

ceiving-boxes, so as to embrace the same. On the outer circumference of the frame B' are arranged flanges b², which are equidistantly connected by bolts b³. The inner circumference of the ring-shaped frame is guided on antifriction-rollers f, which are pivoted to the stationary rings f', which are firmly attached by straps f² to a pair of upright standards S, so that the ring-shaped frame B' may be turned on the rollers around the vertical axis of the rings f' and of the foundation-plate A. A step-by-step or intermittent rotary motion is imparted to the frame B' by a hook-shaped lever C, which is pivoted to a collar C' on the piston-rod D' of the piston of a horizontal steam or air cylinder D, that is provided with suitable inlet and outlet valves, (not shown,) which are operated at the proper time by the attendant. The hook-shaped end of the lever C is moved along the circumference of the ring-shaped frame B' until it engages one of the bolts b³ of the same. Then the piston D' is operated in the reverse direction and the frame B', together with the receiving-boxes B, moved the distance of one-sixth of the circumference of the ring-shaped frame B'. By the next outward motion of the piston and piston-rod D' of the cylinder D the hook-shaped lever C is pressed against the circumference of the ring-shaped frame B' by the spring C², interposed between the collar C' and the hook C, its beveled end permitting it to pass over the bolts b³, while its hook-shaped end engages the bolts on its return stroke.

A second pair of upright standards S' is arranged outside of the foundation-plate A, the upper ends of the standards S and S' being connected by a strong top plate E', while the lower end is connected by a strong base-plate E, each plate being firmly held in position on the screw-threaded ends of the standards by suitable screw-nuts d d, respectively above and below the plates. The top plate E' serves to support a vertical cylinder F, which is provided with suitable inlet and outlet valves and a suitable mechanism for operating the same. To the lower end of the piston-rod F' of the cylinder F is attached a plunger F², the shape of which corresponds to the cross-section of the receiving-boxes, so as to fit snugly into the same. Between the plunger F² and the lower end or head of the cylinder F are interposed a number of cushioning-springs G, which are interposed between a stationary plate g and a sliding plate g', which is guided in stationary brackets or hangers g², attached to the lower end of the cylinder F. After the receiving-boxes B are charged with scraps they are placed one after the other over the stationary anvil M, which fits in an opening of the foundation-plate A and under the plunger F², which is operated so as to produce a series of blows in quick succession for compressing the scraps in the receiving-box until the scraps are compressed

into a square block or package at the lower end. As the scraps are gradually compressed the strokes of the plunger are repeated at greater intervals, the force of the plunger F² being taken up at the end of each upstroke by the cushioning-springs G, so as to facilitate the working of the plunger and cylinder and prevent injury to the latter. 75

In the foundation-plate A is arranged at a distance of one-sixth of its circumference from the anvil an opening a, that is below the adjacent receiving-box, corresponding in shape to the inner circumference of the receiving-box, but of slightly greater size, so as to give a certain clearance to the compressed block of scraps at the lower end of each receiving-box when the block is forced out of the same. For this purpose there is 80 arranged vertically above the opening a in the foundation-plate A a cylinder H, which is provided with suitable inlet and outlet valves and an operating-lever in the same manner as the cylinder F. The plunger H' 85 is attached to the lower end of the piston-rod of the cylinder H and is of smaller size than the plunger F² of the compressing-cylinder F. The plunger H' serves for the purpose of descending into the receiving-box B, which has been moved over the opening a in the foundation-plate, so as to push the compressed package or block of scraps in the lower end of the box out of the same and through the clearance-opening a 90 of the foundation-plate A onto an inclined chute I below the same, as shown in Fig. 1. As each receiving-box is moved after compression by the hook-shaped lever C over the opening a in the foundation-plate A, the knockout or clearing plunger H' is lowered and the compressed block forced out, while at the same time the compression in the following receiving-box below the compression-plunger F² is accomplished. Thus the compression in one box takes place simultaneously with the delivery of the compressed block from the receiving-box without interrupting the regular intermittent motion of the machine for the purpose of removing and delivering the compressed block or package, as was necessary in our application hereinbefore referred to. A special anvil-block and power-cylinder for operating the same are 115 thereby dispensed with, together with the deterioration attendant the same, whereby the operation of our compressing-machine is rendered quicker and more reliable than heretofore. 120

Having thus described our invention, we 125 claim as new and desire to secure by Letters Patent—

1. A machine for compressing detinned and other scraps, which consists of a stationary foundation-plate, a plurality of upright receiving-boxes supported on said foundation-plate, an anvil below one of said receiving-boxes, a clearance-opening in the foundation-plate below the adjacent receiving-box,

means for compressing the scraps in the box above the anvil, means for imparting a step-by-step motion to said receiving-boxes, and means for discharging the compressed scraps from the box then above the clearance-opening, substantially as set forth.

2. A machine for compressing detinned and other scraps, which consists of a stationary foundation-plate provided with an opening, a stationary anvil in said opening, a plurality of upright receiving-boxes supported on said foundation-plate, a vertically-reciprocating plunger above the stationary anvil in the foundation-plate for compressing the scraps in the box above the anvil, a clearance-opening in the foundation-plate below the adjacent receiving-box, a chute below the clearance-opening, means for imparting a step-by-step motion to said receiving-boxes, and a reciprocating plunger above the clearance-opening for delivering the compressed block of scraps at the lower end of the box into the chute, substantially as set forth.

3. A machine for compressing detinned and other scraps, which consists of a stationary foundation-plate provided with an opening, a stationary anvil in said opening, a plurality of upright receiving-boxes supported on said foundation-plate, a clearance-opening, in the foundation-plate at the same distance from the anvil as the boxes are from each other, means for compressing the scraps in the box above the anvil, means for imparting a step-by-step rotary motion to said receiving-boxes for bringing the box with the compressed scraps over the clearance-opening, and means for removing the compressed scraps from the box above the clearance-opening, substantially as set forth.

4. A machine for compressing detinned and other scraps, consisting of a stationary foundation-plate provided with an opening, a stationary anvil in said opening, a plurality of upright receiving-boxes supported on said foundation-plate and provided with reinforcing devices at their lower ends, a ring-shaped frame embracing the lower ends of said receiving-boxes, antifriction-rollers for guiding the inner circumference of said frame, means for intermittently rotating said frame and receiving-boxes, a vertically-reciprocating and spring-cushioned plunger for compressing the scraps successively in one receiving-box after the other passing over the stationary anvil, a clearance-opening in the foundation-

plate below the adjacent receiving-box, and a reciprocating plunger above the clearance-opening for removing the compressed scraps at the lower end of the box, substantially as set forth.

5. The combination, with two pairs of upright supporting-pillars provided with a transverse top plate and a bottom plate, of a foundation-plate provided with an opening, a stationary anvil in said opening, a plurality of receiving-boxes open at both ends supported on said foundation-plate, a ring-shaped frame connecting the lower ends of said receiving-boxes, means for guiding said frame, means for imparting intermittent motion to said frame and receiving-boxes, a vertically-reciprocating spring-cushioned plunger located in line with the anvil in the opening of the foundation-plate and the receiving-box then in position over the anvil, a clearance-opening in the foundation-plate below the adjacent receiving-box, and a reciprocating plunger above the clearance-opening for removing the compressed scraps at the lower end of the box, substantially as set forth.

6. A machine for compressing detinned and other scraps, which consists of a stationary foundation-plate provided with an opening, an anvil in said opening, a plurality of upright receiving-boxes open at both ends supported on the foundation-plate, a platform at the upper ends of said receiving-boxes for charging the same with scraps, a frame embracing the lower ends of said receiving-boxes, means for imparting an intermittent motion to said frame and receiving-boxes, a vertically-reciprocating and spring-cushioned plunger vertically above one of the receiving-boxes for compressing the scraps in the same, a reciprocating clearing-plunger arranged sidewise of the compressing-plunger and at the same distance from the latter as the receiving-boxes are located from each other, a clearance-opening in the foundation-plate vertically below the clearing-plunger, and means for actuating the compressing and clearing plungers, substantially as set forth.

In testimony that we claim the foregoing as our invention we have signed our names in presence of two subscribing witnesses.
